UNITED STATES PATENT OFFICE.

OTTO EGGBRECHT, OF MOMENCE, ILLINOIS, ASSIGNOR TO THE EMERSON TYPEWRITER COMPANY, OF CHICAGO, ILLINOIS, A CORPORATION OF ILLINOIS.

SOLDERING ATTACHMENT.

964,223.

Specification of Letters Patent. Patented July 12, 1910.

Application filed March 8, 1910. Serial No. 548,021.

To all whom it may concern:

Be it known that I, OTTO EGGBRECHT, a citizen of the United States, residing at Momence, in the county of Kankakee and State of Illinois, have invented certain new and useful Improvements in Soldering Attachments, of which the following is a specification.

This invention relates to a soldering attachment more especially designed and adapted for use in soldering type onto the type bars of a typewriter; and has for its object, to produce a device which will enable the type to be soldered to the type bars in such a manner that when the type bars are mounted in the typewriter, the type will be in exact alinement with one another; also, to provide means for supporting the type during the soldering operation, which means will be adjustable; to provide means for centering the type bar so as to bring each type bar into the same exact relation with the type supporting means; and to provide means for locking the type carrier against movement.

The invention further relates to the features of construction and combination of parts hereinafter described and claimed.

In the placing of type upon the type bars of a typewriter, difficulty has been experienced in placing the type so that when the type bar is assembled in the typewriter, the type will be in exact alinement and will all strike at the proper point upon the platen. If an error should be made in positioning the type upon the type bar, it will then be necessary, after the machine is assembled, to readjust the type so as to bring them in alinement, thus necessarily adding to the expense of construction of the machine.

Applicant has devised a means whereby each separate type bar of the bank of type bars is centered in exact relation to a type supporting surface, so that when type has been affixed to each type bar, the type on all of the bars will lie in exact alinement with one another, hence, when the type bars are mounted in the typewriter all of the type will be in perfect alinement. The position of the type supporting surface is such that the type, when lying thereon, will be in proper relation to the type bar, so that when mounted thereon it will strike at the proper point on the platen when the type bar is

mounted in operative position and actuated. 55 By this method, the mounting of the type is a mechanical action and is not dependent upon the skill of an operator to position the type in each instance at the proper point upon the type bar.

In the drawings, Figure 1 is a plan view of the assembled device, showing a bank of type bars mounted in proper relation thereto and showing one of the bars, in the dotted lines, swung into position to receive a type; 65 Fig. 2, a longitudinal section of Fig. 1; and Figs. 3 and 4, enlarged details of the mechanism for adjusting the type supporting surfaces.

The device is mounted upon a base 4, of 70 suitable shape and size, and comprises a type carrier 5, which, as shown, is in the form of a rotatable disk. The type carrier is provided with a plurality of radially extending slots 6, into each of which is entered 75 a type supporting member 7. The type supporting member, as shown, consists of an elongated block 8, provided with a transversely extending groove 9, and also adjacent either side of the groove with matrices 80 10, corresponding to the characters on the type. The type supporting member is beveled at its inner and outer ends 11, and mounted in the type carrier 5 are adjusting members 12, which, as shown, are in the 85 form of ordinary screws. The bevel on each end of the type supporting member is parallel to the bevel on the head of the screw, so that, as is more clearly shown in Figs. 3 and 4, by depressing one of the screws and 90 raising the other, the beveled surfaces of the heads of the screws will act to force the type supporting member in the direction desired within its slot, thus making this supporting member adjustable, so that it may be moved 95 nearer or farther from the center of the type carrier, which adjusts the position of a type 12^a carried thereon, so that when any type bar is brought into position to receive the type, the type will rest against the bar 100 at the proper point.

As shown in Fig. 1, the type carrier is provided with a groove 13, which extends between the grooves 9 in the type supporting members. This groove will serve as an indicator in the adjusting of the type supporting members, so that each supporting member may be positioned in alinement with

the rest. That is, if it becomes necessary to adjust the supporting members a thirty-second of an inch toward the center of the type carrier, by observing the relation of the 5 groove 9 to the groove 13, all of the members may be positioned in alinement with one another without the necessity of measuring the exact distance which each individual supporting member should be moved. The 10 type carrier is provided, around its periphery 14, with a plurality of notches or recesses 15; and these recesses coöperate with a movable locking member 16 to form a means for centering the type carrier after 15 each movement of the carrier necessary to bring the various type supporting members into proper relation with the type bars. The movable locking member 16 is actuated by a handle 17 and is of the ordinary and 20 well known type, so that a detailed description thereof is not deemed necessary. The type carrier is formed with a bearing stud or post 18, which is entered into a recess 19 in the base 4. The mechanism for supporting 25 and holding the type bars is as follows: A plate 20, formed with a longitudinally extending slot 21, is positioned toward the front of the base 4 and, as shown, is in substantial alinement with the center of the 30 type carrier 5. Entered into the slot 21 is a locking member 22 having an enlarged head 23 thereon; and the locking member is adjustably mounted within the base plate 4, as shown in Fig. 2. Extending into the slot 35 21 is a stud 24, which acts as a stop member to bring the plate 20 into proper position to clamp a frame 25 containing type bars, and, as shown in Fig. 1, a plurality of pins 26 are provided, which serve as a means for 40 properly centering the plate. The frame 25 carries a plurality of type bars 27 which, in the form shown, are provided with pins 28, and when the type bars are swung to the 45 position shown in dotted lines in Fig. 1, the pins 28 will enter into a hole 29 formed in a plate 30 attached to the base plate 4.

It is, of course, obvious that the invention is in no way limited to the use of this 50 particular type bar or frame, as various forms of bars and frames could be employed without departing in any way from the spirit of the invention. The bars and frame shown in Fig. 1 are merely for illustrative purposes.

55 The operation is as follows: The type are first placed upon the type supporting members 7, the matrices in the supporting members corresponding to the characters upon the type, so that each supporting member 60 carries a particular type. The type carrier is then rotated until the type which is to be mounted upon the first type bar lying to the left hand side of the bank of bars shown in Fig. 1 is brought into alinement with the 65 hole 29. The type bar is then swung over

and the pin 28 will enter the hole 29 and center the type. The type carrying portion of the type bar will then rest upon the type and will be in proper position to have the solder applied to unite the type to the type 70 bar. The type carrier will then be rotated until the next adjacent notch 15 in the periphery of the type carrier is brought into engagement with the movable locking member 16, at which time the next adjacent type 75 will be in alinement with the hole 29, and the second type bar will then be swung and the type affixed thereto in the manner previously described. This operation will be repeated with the various bars of the bank of 80 bars until type has been affixed to each individual bar, and by arranging the matrix on the type supporting members, so that the type mounted thereon will be in the same relative order that they would be when 85 mounted in the typewriter, the securing of the type to the bars can be performed very rapidly, because the type upon the first supporting member will be the type that belongs on the first type bar, the type on the 90 second member, the one that belongs on the second bar, and so on throughout the bank of bars. In this way no delay is occasioned in the selection of the proper type to place upon the bars, and, at the same time, the 95 alinement of the type will be, for all practical purposes, perfect.

I claim:

1. In a device of the class described, the combination of a type supporting member, 10 means for centering type bars to bring the type carrying portion of each bar into the same position with respect to the type supporting member, and means for adjusting the type supporting member, substantially 11 as described.

2. In a device of the class described, the combination of a movable type supporting member, and means for centering type bars to bring the type carrying portion of each 11 bar into the same position with respect to the type supporting member when the type supporting member is brought into alinement with the type carrying portion of the type bar, substantially as described.

3. In a device of the class described, the combination of a type supporting member, a mounting for type bars, permitting them to be moved into and out of alinement with the type supporting member, and means for 1 centering the type bars to bring the type carrying portion of each bar into the same position with respect to the type supporting member when the bar is brought into alinement with the supporting member, substantially as described.

4. In a device of the class described, the combination of a type supporting member, a mounting for type bars, permitting them to be moved into and out of alinement with 1

the type supporting member, means for centering the type bars to bring the type carrying portion of each bar into the same position with respect to the type supporting member when the bar is brought into alignment with the supporting member, and means for adjusting the type supporting member, substantially as described.

5. In a device of the class described, the combination of a movable type supporting member, means for centering type bars to bring the type carrying portion of each bar into the same position with respect to the type supporting member when the type supporting member is brought into alignment with the type carrying position of the type bar, and means for adjusting the type supporting member, substantially as described.

6. In a device of the class described, the combination of a movable type carrier, and a plurality of type supporting members in the form of adjustable elongated blocks mounted upon said carrier, said supporting members being provided with recesses to accommodate the characters on the type, substantially as described.

7. In a device of the class described, the combination of a movable type carrier, provided with a plurality of grooves, and type supporting members slidably mounted within said grooves, said type supporting members being provided with recesses to accommodate the characters on the type, substantially as described.

8. In a device of the class described, the combination of a type carrier, provided with a plurality of grooves, type supporting members mounted within said grooves, said type supporting members being formed with recesses to accommodate the characters on the type, and means for adjusting the type supporting members within the grooves, substantially as described.

9. In a device of the class described, the combination of a movable type carrier, a plurality of type supporting members mounted upon said carrier, said supporting members being provided with recesses to accommodate the characters on the type, and means for adjusting the type supporting members, substantially as described.

10. In a device of the class described, the combination of a movable type carrier, and a plurality of type supporting members mounted upon said carrier, provided adjacent to their ends with matrices corresponding to the characters on the type, and provided with transversely extending grooves intermediate the matrices, substantially as described.

11. In a device of the class described, the combination of a movable type carrier, having a plurality of grooves therein, type supporting members entered into said grooves, said type supporting members being pro-

vided adjacent their ends with matrices corresponding to the characters on the type, and provided with transversely extending grooves intermediate the matrices, substantially as described.

12. In a device of the class described, the combination of a movable type carrier, a plurality of type supporting members mounted upon said carrier, said supporting members being provided with recesses to accommodate the characters on the type, and means for locking the type carrier against movement, substantially as described.

13. In a device of the class described, the combination of a movable type carrier, a plurality of type supporting members mounted upon said carrier, provided adjacent their ends with matrices corresponding to the characters on the type, and provided with transversely extending grooves intermediate the matrices, and means for locking the type carrier against movement, substantially as described.

14. In a device of the class described, the combination of a type carrier, provided with a plurality of grooves, type supporting members mounted within said grooves, said type supporting members being formed with recesses to accommodate the characters on the type, means for adjusting the type supporting members within the grooves, and means for locking the type carrier against movement, substantially as described.

15. In a device of the class described, the combination of a type carrier in the form of a rotatable disk, a plurality of radially extending grooves in said disk, type supporting members slidably mounted in said grooves, each type supporting member being provided with a recess to accommodate the characters on the type, a plurality of recesses on the periphery of the disk, and a movable locking member adapted to enter said recesses and lock the disk against movement, substantially as described.

16. In a device of the class described, the combination of a movable type carrier, and a plurality of type supporting members mounted upon said carrier, provided adjacent to their ends with matrices corresponding to the characters on the type, and provided with transversely extending grooves intermediate the matrices, the type carrier being formed with grooves extending between the grooves in the type supporting members, substantially as described.

17. In a device of the class described, the combination of a movable type carrier, a plurality of type supporting members mounted upon said carrier, said supporting members being provided with recesses to accommodate characters on the type, the type supporting members terminating at either end in a beveled surface, and adjusting members mounted in the type carriers

and having heads adapted to bear against the beveled surfaces of the type supporting members, substantially as described.

18. In a device of the class described, the combination of a movable type carrier, a plurality of type supporting members mounted upon said carrier, provided adjacent to their ends with matrices corresponding to the characters on the type, and provided with transversely extending grooves intermediate the matrices, the type supporting members terminating at either end in a beveled surface, and adjusting members mounted in the type carriers and having heads adapted to bear against the beveled surfaces of the type supporting members, substantially as described.

19. In a device of the class described, a type supporting member having matrices adjacent its ends to receive characters on type, and provided with a transversely extending recess intermediate the matrices, substantially as described.

20. In a device of the class described, a type supporting member having matrices adjacent its ends to receive characters on type, provided with a transversely extending recess intermediate the matrices, and having its inner and outer edges beveled, substantially as described.
